UNITED STATES PATENT OFFICE.

JAMES M. WALSH, OF STOCKBRIDGE, WISCONSIN, ASSIGNOR TO WALSH HARNESS COMPANY, OF STOCKBRIDGE, WISCONSIN, A CORPORATION OF WISCONSIN.

HAMES.

1,171,567.

Specification of Letters Patent. Patented Feb. 15, 1916.

Application filed January 25, 1915. Serial No. 4,159.

To all whom it may concern:

Be it known that I, JAMES M. WALSH, a citizen of the United States, residing at Stockbridge, in the county of Calumet and 5 State of Wisconsin, have invented certain new and useful Improvements in Hames, of which the following is a specification, reference being had to the accompanying drawing, forming a part thereof.

10 The main objects of this invention are to facilitate the adjustment of hames to collars of different shapes and sizes; to avoid the use of leather fastenings and buckles; and generally to simplify and improve the 15 construction and operation of devices of this class.

The invention consists in certain novel features of construction and in the peculiar arrangement and combination of parts as 20 hereinafter particularly described and pointed out in the claims.

In the accompanying drawing like characters designate the same parts in both figures.

25 Figure 1 is a front elevation of hames embodying the invention as applied to an ordinary horse collar, the upper end of one of the hames being shown in section; and Fig. 2 is an enlarged cross section of one of the hames 30 on the line 2—2, Fig. 1.

The hames 1 and 2, which may be made of any suitable material, as partly of wood and partly of metal, but preferably as shown, entirely of sheet metal pressed into 35 the desired shape, are of round cross section adjacent to their upper ends, which when made entirely of sheet metal, are tubular or hollow, and are provided on their outer sides with longitudinal notched ribs.

40 They are curved and rounded on their inner sides to fit into the crease or channel between the fore and after wales of a collar in the usual way. Metal rings or annular plates 6 and 7, are fitted on the round upper portions of the hames and are adapted 45 to turn thereon. They are formed on their inner sides with notches 8, which are adapted to register with and pass over the ribs 3 between the notches therein when the rings 50 are rotated a half turn on the hames into abnormal position.

The ring or plate 6 is formed or provided on the inner side with an upturned hook 9, and to the end of this hook is pivoted a 55 depending looped or link shaped dog 10,

A chain 11 is pivotally connected by one of its end links with the inner side of the ring or plate 6, as by means of a hook 12 formed on said ring or plate, as shown in Fig. 1. Any of a number of the remaining links 60 of the chain, according to the adjustment of the hames, is adapted to be engaged with the hook 9 on the ring or plate 6, and to be held thereon by the dog 10, which is turned downwardly between it and the hame 2, as 65 shown in Fig. 1, thereby preventing the removal of the link from the hook, excepting when the dog is turned inwardly and upwardly against the hook.

Separation of the rings or plates 6 and 7 70 from the hames is prevented by balls or knobs 13, formed or provided with shanks which are threaded as shown, in the tubular upper ends of the hames.

The flexible connection formed by the 75 rings or plates 6 and 7 and the chain 11 between the hames adjacent to their upper ends, is adjusted up or down for collars of larger or smaller size, by turning the said rings or plates when the hames are removed 80 from a collar, a half turn, till the notches 8 register with the ribs 3, when they may be slipped up or down over the ribs as required, and turned back into working position in engagement with different notches in 85 the ribs.

For adjusting the upper connection for 90 collars of different sizes or widths, when the hames are removed from a collar, the dog 10 is turned back against the under side of the hook 9, thus permitting the chain to be removed therefrom and a different link engaged therewith, so as to lengthen or shorten the connection.

At their lower ends the hames may be 95 provided with any suitable fastening such as terminal hooks 4 and 5 and a chain 17 adjustably attached to the hook 5 and adapted to be forced into and out of engagement with the hook 4 by a lever 14, as shown 100 in Fig. 1.

When the hames are applied to a collar as shown in Fig. 1, the fastenings cannot be displaced or detached, and when the hames are removed from the collar the 105 chain 11 cannot with ordinary handling, be detached from the hook 9.

Various changes in the details of construction and arrangement of parts may be made without departure from the principle and 110

scope of the invention as defined in the following claims.

I claim:

1. The combination with hames removably fitted to a collar and having a round cross section and longitudinal notched ribs on their outer sides adjacent to their upper ends, of rings fitting over and adapted to turn on the round ribbed portions of the hames in engagement with notches in the ribs and having notches in their inner sides adapted to register with and pass over the ribs when the rings are turned into abnormal position, and a flexible connection between the inner sides of the rings adjacent to the notches therein.
2. The combination with hames having a round cross section and longitudinal notched ribs adjacent to their upper ends, of rings fitting over and adapted to turn on the round portions of the hames and having notches in one side corresponding with the ribs and adapted to pass over them when the rings are turned into abnormal position, one of the rings being provided with a hook, and

a chain connected at one end with the other ring and adapted to be detachably engaged by any of a number of its links with said hook.

3. The combination with hames having a round cross section and longitudinal notched ribs adjacent to their upper ends, of rings fitting over the round portions of the hames and into notches in the ribs and having notches in one side adapted to pass over the ribs between the notches therein when the rings are turned on the hames into a certain abnormal position, one of said rings having a hook, a chain pivotally connected with the other ring and adapted to be engaged by any of a number of its links with said hook, and a dog pivotally connected with the hook and adapted to prevent accidental disengagement of the chain therefrom.

In witness whereof I hereto affix my signature in presence of two witnesses.

JAMES M. WALSH.
